STRING HOLDER FOR SAUSAGE CASINGS

Hans J. Jaworski, Milwaukee, Wis.

Application June 21, 1935, Serial No. 27,686

5 Claims. (Cl. 24—243)

This invention appertains to a novel device for facilitating the tying of the terminals of the casings of sausages, particularly sausages of the ring or straight type, such as liver sausage, bologna, etc.

In tying such sausages, it is customary to place a knot intermediate the ends of a group of relatively short lengths of cord or string. This bunch of string is then placed over a nail or hook at 10 the knot portion at one side of the work bench. The ends of the string on one side of the knot are used to tie the casing ends, after which the string ends are severed adjacent to the knot. The string ends on the other side of the knot are 15 then used to tie other casing ends.

When these casing ends are tied, the strings are severed at the knot. The knot is then thrown away, resulting in a material waste of cord or string. Further, much time is consumed in forming the group of strings and tying the knot. The knot hanging from the hook or nail does not 20 firmly hold the group of cords, and consequently each length of cord has to be firmly held during the tying of a casing end.

It is, therefore, one of the prime objects of my 25 invention to provide novel means for holding a series of cords directly at the point of the tying of the casing ends, and without the necessity of the cutting of the strings in lengths, and the 30 tying of the knot intermediate the ends of the group of strings.

Another important object of my invention is the provision of means for using a group of strings directly from a roll or reel, with means 35 located directly on the table for firmly clamping the group of strings against slipping during the tying operation of the casing ends, the clamp allowing the group of strings to be fed forwardly as needed, without waste.

A further object of my invention is the provision of a clamp for releasably and tightly holding a length of string against movement, which 40 includes a movable jaw, with means for urging the jaw into its gripping position, and means for 45 raising the jaw to its elevated inoperative position.

A further salient object of my invention is the provision of means carried by the clamp for initially holding and guiding a group of strings 50 during the placing of the group of strings between the clamping jaws.

A still further object of my invention is to provide an improved string clamping device for facilitating the tying of sausage casing ends of the 55 above character, which will be durable and ef-

ficient in use, one that will be simple and easy to manufacture, and one which can be placed upon the market at a reasonable cost.

With these and other objects in view, the invention consists in the novel construction, arrangement, and formation of parts, as will be hereinafter more specifically described, claimed, and illustrated in the accompanying drawings, in which drawings:

Figure 1 is a side elevation of my improved 10 device.

Figure 2 is a fragmentary longitudinal section 15 through the improved device, taken substantially on the line 2—2 of Figure 3, looking in the direction of the arrows.

Figure 3 is a top plan view of the improved 20 device, with parts of the operating handle shown broken away.

Figure 4 is a fragmentary detail sectional view taken substantially on the line 4—4 of Figure 20 3, looking in the direction of the arrows.

Figure 5 is a similar view taken substantially 25 on the line 5—5 of Figure 3, looking in the direction of the arrows.

Figure 6 is a central transverse section taken 30 through the improved device substantially on the line 6—6 of Figure 1, looking in the direction of the arrows.

Figure 7 is a fragmentary longitudinal section 35 through a modified form of the invention.

Figure 8 is a fragmentary transverse section 40 taken on a reduced scale on the line 8—8 of Figure 1, looking in the direction of the arrows, illustrating the guide for the cord.

Referring to the drawings in detail, wherein 45 similar reference characters designate corresponding parts throughout the several views, the letter A generally indicates my improved device for facilitating the tying of sausage casing ends, and, as shown, the same includes a base block 10 50 having a stationary jaw 11 formed thereon. The active face of the jaw 11 is preferably grooved, serrated, or otherwise treated so as to form an efficient gripping surface. The opposite ends of the block 10 can be provided with attaching feet 45 or lugs 12, which can be clamped to or secured on the work table in any desired manner, such as by the use of screws 13. Formed on each side of the jaw are upstanding side walls 14, the upper edges of which have formed therein inclined 55 slots 15 terminating in bearing openings 16.

Removably mounted between the side walls or plates 14 is a vertically slideable jaw 17. The lower face of this jaw is preferably provided with a centrally disposed, longitudinally extending rib

18', which has its lower surface grooved, serrated, or otherwise treated to form a companion clamping member for the stationary jaw.

Secured to the opposite sides of the movable jaw 17 are side plates 18. These side plates 18 have formed therein vertical slots 19 for the reception of a transversely extending pivot shaft 20. The terminals of the pivot shaft 20 are fitted within the bearing openings 16 formed in 10 the side walls 14 of the base.

Secured to the shaft 20 is the operating handle 21, and the forward end of the operating handle has formed thereon the actuating cam 22. This cam 22 is adapted to forcibly urge the jaw 17 15 into its lowered gripping position when the handle 21 is swung to a lowered position, as shown in Figures 1 and 2.

The opposite ends of the operating cam 22 have formed thereon cams 23, which are received in 20 cam tracks or ways 24 formed in the inner faces of the side plates 18 of the movable jaw 17. When the handle 21 is swung to an elevated position, the operating cam 22 is moved away from the jaw 17, and the cams 23, working in the cam 25 tracks 24, will lift up the side plates 18 and carry the jaw 17 to an elevated raised position.

As heretofore stated, the device A is secured to a work bench or table at the point where the sausage casing ends are to be tied, and the group 30 of strings S is fed down from a reel and placed between the stationary and movable jaws. Obviously, when the handle 21 is swung to its lowered position, the group of strings S will be firmly held against slipping movement. The casing 35 ends can then be quickly and conveniently tied, and after the desired number are tied, the strings S are severed, after which the movable jaw 17 is released, and the group of strings S is again pulled forwardly and clamped.

40 During the initial placing of the strings S in position, the removable jaw 17 can be removed from the block 10, and after the strings are in place the jaw 17 can again be placed in position.

To facilitate the initial placing of the strings 45 in position, the block 10, in rear of the movable jaw 17, can carry a guide 25 for the string or cord. The guide 25 is pivotally connected to the block 10 by means of a pivot pin 25', and the guide can be swung open to facilitate the placing 50 of the cords therein. A releasable bale lever 26 is hingedly carried by the block, and is adapted to be swung over the front part of the guide to hold the same normally against opening movement.

55 If desired, the side walls 14 can have pivotally connected thereto bearing blocks 27, the lower faces of which at their forward terminals are recessed for the ends of the shaft 20. These bearing blocks 27 are adjustably held in proper 60 position by means of screws 28, which pass through the blocks 27. The lower ends of the screws are threaded into bosses or webs 29 formed on the outer faces of the walls 14. Thus the blocks 27 can be brought into more or less contact with the shaft terminals by turning the 65 screws 28.

My improved device forms an exceptionally simple and novel means for holding a plurality of cord ends against movement, and facilitates 70 the tying of sausage casing ends. The device is so constructed as to operate efficiently under all conditions, and will not become clogged by pieces of meat and the like.

Where it is desired to hold a single length of 75 cord, the device can be simplified, and in Figure 7

I have shown one of my devices for holding a single cord.

This device is generally indicated by the reference character M, and includes a stationary block 30. The block 30 has formed thereon the 5 side walls 31, and a jaw face 32 is formed on the block intermediate the side walls. Slidably received between the side walls 31 is the movable clamping jaw 33, and this jaw carries upstanding side plates 34.

Extending through the side plates 34 is the operating shaft 35, the terminals of which are received within inclined slots 36 formed in the walls 31. This shaft carries the cam 37 for forcing the jaw 33 toward the block 30. This cam 15 has formed thereon or secured thereto the operating handle 38. Small cams 39 are formed on the ends of the cam 37, and these cams 39 are received within cam tracks 40 formed in the inner 20 faces of the side walls 31.

In this form of my invention, the block 30 can be provided with an end wall 42 disposed between the side walls 31, and this end wall is provided with a guide opening 43 for the string or cord C. 25

Changes in details may be made without departing from the spirit or the scope of my invention, but what I claim as new is:

1. A string-holder comprising a base having a jaw face and upstanding side walls, the side walls being provided with inclined slots terminating in bearing openings, a movable jaw received between the side walls, a transversely extending shaft loosely carried by the movable jaw and received in the bearing openings through said 30 slots, a cam on said shaft, a handle carried by the cam for moving said cam into and out of engagement with the movable jaw, and means carried by the cam for forcibly raising the movable jaw when the handle is in its inoperative position. 40

2. A string-holding device comprising a base having a jaw face and upstanding side walls, a movable jaw received between said side walls, side plates carried by the movable jaw having cam tracks on their inner faces, a transversely extending shaft rotatably carried by the side walls and loosely extending through the side plates, a cam on said shaft, an operating handle on the cam for moving the cam into and out of contact with the movable jaw, and cams on the terminals of the first mentioned cam received within said cam tracks, as and for the purpose specified. 45

3. A string-holding device comprising a base having a longitudinally extending slot and upstanding side walls, the bottom wall of said slot 55 being provided with grooves, a movable jaw received between the side walls having a depending rib fitted in the groove, the lower face of the rib being provided with transversely extending grooves, side plates carried by the movable jaw, a transversely extending shaft slidably carried by the side plates and rotatably supported by the side walls, a cam on said shaft, an operating handle for the cam, the inner faces of the side plates being provided with cam tracks, and cams formed 60 on the terminals of the first mentioned cam received in said cam tracks. 65

4. A string-holding device comprising a base having a longitudinally extending slot and upstanding side walls, the bottom wall of said slot 70 being provided with grooves, a movable jaw received between the side walls having a depending rib fitted in the groove, the lower face of the rib being provided with transversely extending grooves, side plates carried by the movable jaw, a 75

transversely extending shaft slidably carried by the side plates and rotatably supported by the side walls, a cam on said shaft, an operating handle for the cam, the inner faces of the side plates being provided with cam tracks, cams formed on the terminals of the first mentioned cam received in said cam tracks, and adjustable bearing blocks for the shaft carried by the side walls.

5. A string-holding device comprising a base having a longitudinally extending slot and up-standing side walls, the bottom wall of said slot being provided with grooves, a movable jaw received between the side walls having a depending rib fitted in the groove, the lower face of the

rib being provided with transversely extending grooves, side plates carried by the movable jaw, a transversely extending shaft slidably carried by the side plates and rotatably supported by the side walls, a cam on said shaft, an operating handle for the cam, the inner faces of the side plates being provided with cam tracks, cams formed on the terminals of the first mentioned cam received in said cam tracks, adjustable bearing blocks for the shaft carried by the side walls, and a releasable guide for the string arranged in advance of the movable jaw.

10. HANS J. JAWORSKI.
